UNITED STATES PATENT OFFICE

161,745

SPOON OR SIMILAR ARTICLE

Mary Parker Fleming, Newark, N. J., assignor to Oneida Ltd., Oneida, N. Y., a corporation of
New York

Application October 6, 1950, Serial No. 12,469

Term of patent 14 years

(Cl. D54—12)

To all whom it may concern:

Be it known that I, Mary Parker Fleming, a citizen of the United States, residing at Newark, county of Essex, and State of New Jersey, have invented a new, original, and ornamental Design for a Spoon or Similar Article, of which the following is a specification, reference being had to the accompanying drawing, forming a part thereof, in which:

Figures 3, 4, 5 and 6 are sections taken on the respective lines 3—3; 4—4; 5—5 and 6—6 of Figure 1.

The essential features of my design for a spoon or similar article reside in the configuration of the handle in combination with the particular type of ornamentation as applied thereto.

I claim:

The ornamental design for a spoon or similar article, substantially as shown and described.

MARY PARKER FLEMING.
